UNITED STATES PATENT OFFICE.

LLOYD A. WILLIAMS, OF BURLINGTON, KANSAS.

SHOCKING-MACHINE.

1,190,349.

Specification of Letters Patent. Patented July 11, 1916.

Application filed April 8, 1915. Serial No. 20,074.

To all whom it may concern:

Be it known that I, LLOYD A. WILLIAMS, a citizen of the United States, residing at Burlington, in the county of Coffey and State of Kansas, have invented a new and useful Shocking-Machine, of which the following is a specification.

This invention relates to machines for forming shocks and is more particularly an improvement upon the structure disclosed in my patent issued on January 26, 1915, No. 1,126,604.

One of the objects of the invention is to provide a shocking machine of the general type disclosed in my patent before mentioned but which machine has improved means under the control of the bundles being delivered to the shock former, for placing the twisting or tying mechanism into operative connection with its driving means.

Another object of the invention is to provide simple and efficient means for packing the bundles within the shock former where they are subjected to the action of the tying mechanism.

A further object is to provide means whereby the shock is ejected from the shock former so that the butt end of the shock will be forcibly shifted downwardly into engagement with the ground.

Another object of the invention is to provide shock forming and releasing means of improved form with which co-operates a locking mechanism constituting efficient means for holding said shock support in active position.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings, the preferred form of the invention has been shown.

In said drawings—Figure 1 is a front elevation of a shock former embodying the present invention. Fig. 2 is a top plan view thereof. Fig. 3 is an enlarged elevation of the packing and twisting or tying mechanism. Fig. 4 is a plan view of the twisting spiral and adjacent parts. Fig. 5

is a plan view of one corner portion of the downwardly yieldable shock supporting means. Fig. 6 is a section on line A—B Fig. 5. Fig. 7 is a rear elevation of the structure shown in Figs. 5 and 6, parts being broken away. Fig. 8 is a plan view of a portion of the shock support, one of the guides adjacent thereto being shown in section. Fig. 9 is a section on line C—D Fig. 3.

Referring to the figures by characters of reference, 1 designates the base frame of the shock former open at its back and having a supporting caster connected to the front portion thereof, as shown at 2.

The base frame has standards 3 extending upwardly from the inner sides thereof and preferably formed of angle strips as shown particularly in Fig. 8, these standards constituting guide rails as hereinafter set forth. Angle strips 3' form connections between the standards and one of them may be provided with brackets 4 constituting bearings for the upper shaft 5 of an endless elevator 6. This elevator is preferably formed of chains mounted on sprockets 7 secured to the shaft 5, said chains having outstanding fingers 8 and being also mounted on sprockets 9 secured to a shaft 10 which is journaled within the lower portion of an extension frame 11 supported beyond the side of the base frame 1. A main drive wheel 12 is arranged between base frame 1 and extension frame 11 and a sprocket wheel 13 rotates therewith.

Standards 14 extend from the lower ends of the extension frame 11 and are provided, at their lower ends, with laterally extending brackets 15 adapted to be connected, as by means of suitable couplings 16, to a part of a harvester not shown. These brackets support guides 17 which lie close to the path of the fingers 8 and are adapted to be engaged by the chains of the elevator 6 which are extended forward to sprockets 9 to form a table designed to receive bundles as they are ejected from the harvester and binder.

Reinforcing rails 18 extend upwardly from the standards 14 and along lines substantially parallel with the extension frame 11, these rails being preferably attached to the standards 3 and merging into arches 19 which overhang the base frame 1 and merge into or are secured to other standards 20 which extend upwardly from the outer side of the base frame 1. Strips 21 connect the arches 19 and retaining rods 22 may be se-

cured to the connecting strips and be extended downwardly between the outer standards 20. The space between the arches 19 and the uppermost portion of the elevator constitutes a throat through which bundles are delivered from the elevator and into the shock former made up of the base frame 1, standards 3 and 20 and arches 19.

A front strip 23 is connected to the arches 19 and has depending spring fingers 24 supporting retaining strips 25 which extend downwardly to points close to the base frame 1 and serve to prevent the butt ends of the bundles delivered to the shock former, from shifting forwardly undesirable distances. The strip 23 and the parts supported thereby are adapted to be adjusted forwardly or rearwardly by a lever 26 connected, by a link 26', to longitudinally slotted slides 27' to which the strip 23 is secured.

The shaft 5 hereinbefore referred to is provided at one end with a bevel gear 27 which receives motion, through a gear 28, from a short shaft 29 to which is secured a sprocket 30, this sprocket receiving motion, through a chain 31', from the sprocket 13 hereinbefore referred to. The other end of shaft 5 is connected to a flexible shaft 31 which, in turn, is secured to a clutch member 32 mounted for rotation upon a stem 33 provided at one end with diverging arms 34 each merging into a coil 34'. The stem 33 is journaled within a bracket 35 supported pivotally upon a slide 35' mounted on the upper connection 3' and above the throat hereinbefore referred to, there being a fixed arm 36 upon the slide and to which is secured one end of a spring 37, the other end of the spring being connected to the bracket so that said bracket is normally held with the stem 33 inclined downwardly into the space in the upper portion of the shock former. The bracket 35 has an arm 38 extending therefrom to which is adjustably connected an arm 39 having an integral shoe 40, said shoe being located below and to one side of the twisting coil 34. As shown particularly in Fig. 3, arm 39 is pivotally connected to arm 38 at 41 and has a holding bolt 42 shiftable through any one of the series of apertures 43 so that it is thus possible to adjust the shoe 40 angularly relative to the bracket 35. A hook 44 is secured to the arm 39 and is preferably shaped as shown in Figs. 3 and 4, this hook serving to pick up a wisp of material from the bundle passing under the arm 39 and holding it in position to be engaged by the twisting coils 34' as hereinafter pointed out. A knife 45 is secured to the arm 38 so as to cut off any material which might twist about the stem 33.

A disk 46 is feathered on the stem 33 and has a clutch member 47 revoluble there-

with. A spring 48 is connected to the disk 46 and serves to hold said disk normally in position with its clutch member 47 out of engagement with the clutch member 32. A lever 49 is fulcrumed on the bracket 35 and is connected by a link 50 to another lever 51 fulcrumed on an arm 52 fixedly mounted on slide 35'. A rod 53 connects this lever 51 to an intermediate portion of an actuating lever 54 which is hung from slide 35' and within the throat of the shock former where it will be engaged and elevated by the bundles as they are successively delivered into the shock former. Obviously each time a bundle passes under lever 54 from the elevator, it elevates said lever 54 until it has cleared the same, and as this lever 54 is raised, motion is transmitted therefrom to the lever 49 which acts to clamp against the disk 46 and shift it along the stem 33 so as to bring the clutch member 47 into engagement with clutch member 32, this operation serving to couple the flexible shaft 31 to the stem 33 to cause the stem 33 and twisting coils 34' to rotate. Spring 48 is elongated during this operation and, as soon as lever 54 drops to initial position, spring 48 will return the clutch member 47 to its initial position out of engagement with clutch member 32, thus uncoupling shaft 31 from stem 33.

In order that the stem 33 may be automatically adjusted so as to extend over the middle portion of the shock being formed, a lever 50' is fulcrumed on the top of the shock former and is connected, by a link 51', to the link 26' and, by a link 52', to the slide 35'. Thus it will be seen that as the strips 25 are pushed forwardly by the lever 26, motion will be transmitted from the link 26' through link 51' to lever 50' which, in turn, will transmit motion through link 52' to the slide 35' which will be automatically centered above the shock being formed.

Mounted on the shaft 5 at desired intervals are eccentrics 55 each of which engages a strap 56 carrying a substantially V-shaped packing finger 57. This packing finger has a depending arm 58 secured to one end of a link 59, the other end of the link being pivotally connected to the extension frame 11. Consequently during the rotation of the shaft 5 and the eccentrics 55, the packing fingers 57 will be caused to rise upwardly back of each bundle elevated and push said bundle inwardly and downwardly within the shock former and under and past the lever 54. By providing the link 59 in connection with the eccentric 55, the point of each packing finger is given a throwing or clutching action which is very desirable.

The guide rails or standards 3 are movably engaged by grooved wheels 60 carried by yokes 61 which are secured to a side bar

62 forming a part of the shock supporter. This bar has an upwardly extending arm 63' at one end which is engaged by a supporting spring 64', this supporting spring being suspended from the upper end portion of one of the standards or guide rails 3. Thus the bar 62 is held normally supported close to but below the throat of the shock former. A supporting finger 63 is fixedly connected to the rear end portion of the bar 62 and is extended substantially horizontally from one side to the other of the shock former. Another shock supporting finger 64 is pivotally mounted upon the bar 62 near the front end thereof and is connected, by a yoke 65 to another pivotally mounted finger 66 preferably disposed midway between the fingers 63 and 64. The finger 64 has that end thereof nearest the standard 3 downturned, as at 65', and connected, by spring 66' to a hanger 67 carried by the bar 62. This spring 66' serves to hold the finger 64 normally horizontal. A roller 68 is extended from one side of the finger 64 and is normally overhung and engaged by the curved arm 69 of a locking lever 70 which is fulcrumed on a block 71 fixedly connected to the bar 62. A spring 72 connects one arm of this lever 70 to the block so as to hold the curved end portion of the lever normally in the path of the roller 68. Another roller 73 is mounted in the upper end portion of lever 70 and is adapted to be engaged by a roller 74 connected to the free end portion of a latch lever 75 which is fulcrumed preferably on a bracket 76 carried by the block 71. A spring 77 engages the latch lever 75 so as thus to hold the roller 74 normally pressed against lever 70 and the roller 73, thus to hold said lever against movement about its pivot and, consequently, locking the curved arm 69 of lever 70 in the path of roller 68 so that the finger 64 cannot swing downwardly to release the load carried thereby. A dog 78 is pivotally connected to the block 71 and a spring 79 connects this dog to the arm 69 so that, when the roller 68 is held in engagement with the arm 69, the dog 78 is pulled upwardly against the roller as shown. This dog is so proportioned that when arm 69 is swung away from the roller 68, and the said roller is moved out of its normal position, the spring 79 will pull the dog 78 upwardly against the arm 69 so as thus to lock said arm out of the path of the roller 68 and permit said roller to swing back to its normal position without opposition from the arm 69. A bell crank lever 80 is mounted upon one side of the block 71 and one arm of this lever extends under the latch lever 75 while the other arm extends downwardly and is slightly curved as shown at 81, so that when the shock support made up of the bar 62 and the fingers carried thereby is moved downwardly against the action of the supporting springs 64' and under the

weight of the load, this arm 81 will ultimately move against a trip arm 82 carried by the base frame 1.

As shown in Fig. 1, spring retaining fingers 83 are secured to one of the connections 70 21 and project downwardly between the fingers of the shock supporter when said supporter is in its normal position, these retaining fingers 83 being disposed in the path of the bundles as they are delivered into the 75 shock former by the elevator 6.

As shown particularly in Fig. 6 a shield 88 is preferably erected over the parts 75, 76 and 70 so as to keep chaff and the like away from them. Furthermore a metal 80 shield such as shown at 89 may be arranged between the chains of the elevator 6.

As shown in Figs. 1 and 2, a caster may be connected to the outer side of the base 1 of the frame of the shock former, this caster 85 including a stem 90 adjustably mounted in a block 91 extending outwardly from the side of the frame of the shock former, there being a set screw 92 in the block for engaging the stem to hold the stem against movement. This caster is to be attached to the machine when the shock former is uncoupled from the harvester and is to be moved from place to place. At other times the caster can be removed. 95

As the bundles of material to be formed into a shock are delivered from the binding mechanism, they are engaged by the fingers 8 of the elevator, and carried upwardly to the throat of the shock former. Each bundle as it passes through the throat of the machine is carried under and actuates the lever 54, the packing fingers 57 serving to thrust the bundles into the shock former and onto the supporting fingers 64, 66 and 63. 100 105 As each bundle passes under the lever 54 and raises it, the stem 33 is coupled to the continuously rotating flexible shaft 31 so that the twisting coils 34' will thus be brought into action. The bundle in passing under the shoe 40 is engaged by the hook 44 which pulls a wisp from the bundle and holds it where it will be engaged by the twisting coils 34'. This wisp remains in engagement with the coils and is twisted with a wisp 110 from the next following bundle. As the bundles are thus discharged into the shock former they are all tied together by the mechanism described, it being apparent that the shoe 40 always holds the coils 34' the 115 proper distance from the top of the bundle, upward and downward swinging movement of the coil and shoe being permitted without necessarily throwing the clutch member 47 into engagement with the clutch member 32. 120 125 As the various bundles are tied together and new bundles admitted to the shock former, the weight supported by the fingers 63, 64 and 66 is increased so that the spring 64' is elongated, the bar 62 moving downwardly 130

along the guide standards 3 until the arm 81 of bell crank lever 80 strikes the stationary arm or bracket 82 whereupon the latch lever 75 is elevated out of the path of roller 73 and the roller 68 pushes upwardly against the curved arm 69 (see Fig. 6) so that the two fingers 64 and 66 are thus free to swing downwardly. During the downward movement of the fingers the spring 79 pulls on the dog 78 which is brought to position against the arm 69 and locks the lever 70 elevated against the action of its spring 72, as shown by dotted lines in Fig. 6. When the fingers 64 and 66 swing downwardly under the weight of the load carried thereby, the butt ends of the bundles forming the shock and which are at the front of the machine, will drop downwardly onto a lever 84 which extends under the front portion of the base frame 1 and in the path of the dependings butts of the bundles. The outer end of this lever is connected by a rod 85 to an ejecting lever 86 extending over the front portion of the shock former. Consequently when lever 84 is moved downwardly by the depending butt ends of the bundles, motion will be transmitted therefrom through rod 85 to lever 86 which will push downwardly on the uppermost bundles of the shock, thus forcibly ejecting the butt end of the shock. As said butt end of the shock turns into engagement with the ground, the fingers 64, 66 and 63 are relieved of the weight of the shock and are promptly returned to elevated positions by the springs 64', this upward movement of the fingers 63, combined with the forward movement of the shock former, serving to swing the deposited shock to an upright position with its butt end on the ground. A spring 87 returns the levers 84 and 86 to their initial positions after the ejection of the shock. As soon as the fingers 64 and 66 are relieved of the weight of the shock, the spring 66' returns them to their initial positions so that the roller 68 will strike against dog 78 and move it out of engagement with arm 69, thus allowing the spring 72 to swing said arm 69 to normal or locking position, while at the same time spring 77 will swing the latch lever 75 downwardly into locking position as shown in full lines in Fig. 6. Thus the parts are all reset to repeat the operation described. An adjustable stop 74' can be provided for limiting the downward movement of the arm 75.

What is claimed is:

1. In a machine of the class described, a yieldingly supported structure, a member fixed thereto for engagement with the top of a formed shock, a pivoted member for engagement with the butt end of the shock, means for directing bundles onto said members to lower the structure, means for locking said pivoted member against movement relative to the yieldingly supported struc-

ture, means for automatically unlocking the pivoted member to drop the butt end of the formed shock when said yieldable structure is lowered under the weight of its load to a predetermined point, and means operated by the released butt end of the shock for pushing downwardly on the upper side of the butts. 70

2. In a machine of the class described, the combination with a shock former and means for directing bundles thereinto to form a shock, of a yieldingly supported structure, a finger fixed relative thereto and adapted to extend under the top of the formed shock, a finger pivotally connected to said structure and adapted to extend under the butt end of the formed shock, means for locking the pivoted finger against movement with respect to said yieldingly supported structure, means for automatically unlocking the pivoted finger when the yieldingly supported structure is lowered to a predetermined position under the weight of its load, an actuating lever in the path of the released butt end of the shock, an ejecting lever above the shock, and means for transmitting motion from the actuating lever to the ejecting lever to press the butt end of the shock downwardly during the release of said pivoted finger. 85

3. In a shock forming machine, the combination with a yieldingly supported structure, a finger fixedly connected thereto, and a finger pivotally connected to said structure, of resilient means for holding the pivoted finger normally in raised or active position, a member projecting laterally from the pivoted finger, a locking lever extending into the path of said member, means for holding the locking lever in such position, means operated by the descent of the yieldingly supported structure for releasing said holding means from the locking lever to free said laterally projecting member on the finger, and means operated by the locking lever when shifted out of holding position, 100 for engaging said locking lever to hold it out of the path of the laterally projecting member on the finger. 105

4. In a shocking machine, the combination with a yieldingly supported structure, a finger fixedly connected thereto, and a finger pivotally connected thereto, of yielding means for holding the pivoted finger normally in active position, a projection upon one side of said finger, a locking lever normally extending into the path of the projection, a holding lever normally engaging the locking lever to maintain the same in the path of the projection, a pivoted dog extending under the projection, and a yieldable connection between the locking lever and the dog, said connection constituting means for lifting the dog into engagement with the locking lever when said lever is shifted out of engagement with the projec- 125 130

tion, thereby to hold said lever out of the path of the projection, and for disengaging the holding lever from the locking lever when the yieldable structure is lowered to a predetermined position, thereby to release the load supported by the fingers.

5. In a shock forming machine, the combination with yieldable shock supporting means, and means for automatically releasing the butt end of the supported shock when lowered to a predetermined position, of means operated by the released butt end of the shock for pressing downwardly upon said butt end to eject it downwardly into engagement with the ground.

6. In a shock forming machine, the combination with yieldable shock supporting means, and means for automatically releasing the butt ends of the supported shock when lowered to a predetermined position, of means operated by the released butt end of the shock for pressing downwardly upon said butt end to eject it downwardly into engagement with the ground, said means including an actuating lever extending under the butt end of the shock, an ejecting lever extending over the butt end of the shock, and means for transmitting motion from the operating lever to the ejecting lever.

7. In a shocking machine, the combination with a shock former having an inlet or throat, of a twister tiltably mounted within the other portion of the former and adjacent the throat, a clutch member slidable upon and revolute with the twister, a continuously revolute clutch member, yielding means for holding the clutch member normally disengaged, means for elevating bundles successively to the throat, means operated by each bundle during its passage

through the throat for shifting one of the clutch members into engagement with the other clutch member, thereby to actuate the twister, means movably mounted in the throat for packing bundles within the shock former, such packing means including an eccentric, a finger supported and actuated thereby, means for rotating the eccentric, and a link mounted at one end upon a fixed pivot and at its other end connected to the finger.

8. In a shock forming machine, the combination with a shock former having a throat or inlet, and front strips movably connected to the former, of a revolute twisting element yieldingly supported adjacent said inlet or throat, means operated by the movement of the front strips relative to the shock former for shifting the twisting element to center it above the shock being formed, and means for actuating the twisting element.

9. In a shock forming machine, the combination with a shock former having a throat or inlet, and front strips movable forwardly relative to the former, of a slide, a stem mounted for rotation and movable with the slide, diverging arms upon the stem, a twisting coil at the free end of each arm, means for actuating the stem, and means operated by the movement of the front strips for shifting the slide to center the twisting coil above the shock being formed.

In testimony that I claim the foregoing as my own, I have hereto affixed my signature in the presence of two witnesses.

LLOYD A. WILLIAMS.
